UNITED STATES PATENT OFFICE.

JAMES WEIR FRENCH, OF ANNIESLAND, GLASGOW, SCOTLAND, ASSIGNOR TO BARR AND STROUD, LIMITED, OF GLASGOW, SCOTLAND.

PERISCOPIC APPARATUS FOR RANGE FINDING, HEIGHT FINDING.

Application filed October 24, 1922, Serial No. 596,666, and in Great Britain November 1, 1921.

This invention relates to apparatus comprising two optical systems, one a first optical system of the range-finder class, the other a second optical system of the periscope class, the first system extending, say, horizontally, the second system extending, say, vertically and downwardly from the first system, and having the two systems associated so that rays from the first system may 10 be directed into the second system.

The axes of the two optical systems remain perpendicular to one another, and in the following description it will be assumed that the axis of the first system is horizontal 15 and that of the second system is vertical.

In apparatus to which this invention relates the first system requires to be capable of angular adjustment about its horizontal axis, and the object of this invention is to 20 make provision whereby rays passing from the first system at all angles to which it is adjustable about its horizontal axis may be automatically directed vertically into the second system and whereby the position of 25 the focal plane of the image as seen in the second system may be maintained constant, and further to enable angular adjustment of the first system about its horizontal axis to be extensive.

30 The first system may be for rangefinding, heightfinding and the like, and will hereinafter be referred to as a rangefinder system and the second system as a periscope system.

The rangefinder system may be of the coincidence type associated with one periscope system or of the stereoscopic type in which case there may be two periscope systems or their equivalent, but the invention is not restricted to these particular types of range-finders or periscope systems.

Some examples of construction according to this invention comprising a rangefinder system of the self contained base type and a single periscope system will now be described with reference to the accompanying drawings, in which:—

Figure 1 is an elevation and Figure 2 is a side view illustrating one form of construction.

50 Figure 3 is a sectional elevation on a larger scale of a portion of Figure 1.

Figure 4 is an elevation illustrating a modification.

55 Figure 5 is a broken elevation partly in section and Figure 6 is a sectional plan, the

section taken being about the line XX of Figure 5, illustrating mechanism to be described.

In the construction illustrated at Figures 1, 2 and 3 a watertight upright casing A for the periscope system is provided having a watertight head casing A¹, which extends laterally from opposite sides of the upright casing A, within which a rangefinder B is so mounted as to be capable of angular adjustment about its longitudinal horizontal axis. For the admission of the rays of light to the apertures of the rangefinder, the head casing A¹ is provided with watertight casing windows C of the requisite strength, 65 the vertical lengths of which are such as to afford an unrestricted aperture for the beams of light within the required limits of the altitudinal rotation.

Within the head casing, see Figure 3, the 75 rangefinder B may be supported upon roller, ball or other bearings which permit of its rotation about its longitudinal horizontal axis, for example, rollers 1 may be provided, and means may be provided for restricting 80 the endwise movement of the rangefinder, for example, a roller 2 may be mounted upon the rangefinder B to engage with a groove formed in the interior of the head casing, the groove being part of a circular 85 groove cut concentric with the longitudinal horizontal axis of the rangefinder and in a plane normal to the axis.

Means of a kind described later are provided for the direction of the emergent rays 90 of light from the angularly adjustable rangefinder into the optical system of the periscope.

For angular adjustments of the rangefinder about its longitudinal horizontal axis 95 mechanism is provided which may be housed within the upright casing A and its head A¹. For example, as illustrated, see Figures 1 and 2, a shaft capable of rotation and having a hand wheel D may be mounted to extend 100 upwards through the upright casing A and be furnished at its head with a bevel pinion 3 in mesh with a bevel spur rack 4 fixed to the tubular casing of the rangefinder. In Figure 3 the pinion 3 and rack 4 are not 105 shown.

In the construction illustrated at Figure 4 the periscopic upright casing A is provided with a covering head having tubular sleeves A² which extend laterally from op- 110

posite sides. The sleeves A^2 are open at their outer ends for the reception of the rangefinder B the outer ends of which project beyond the outer ends of the sleeves, 5 and in order to exclude water from the casing A watertight glands are provided between the sleeves A^2 and the body of the rangefinder of a character which permits the required angular adjustment of the range- 10 finder about its longitudinal horizontal axis.

In this particular construction the portions 15 of the rangefinder casing which are located within and project beyond the glands are themselves watertight, and the rangefinder windows B^1 are made sufficiently strong to withstand the water pressure when the rangefinder is submerged. As in the construction Figures 1, 2 and 3, means are provided for supporting the rangefinder B with- 20 in the sleeves A^2 , for constraining it against endwise movement, for angling the rangefinder about its longitudinal horizontal axis, and for directing the emergent beams from the rangefinder into the periscope system 25 contained within the upright casing A.

It is desirable that, as the rangefinder B is rotated in altitude, the image of the target should appear in the field of the periscope whenever the rangefinder is directed 30 upon the target and that altitudinal movement of the rangefinder relative to the periscope should not affect the orientation of the image of the field of view or to a serious extent the focus of the image.

35 An example of one method in which these conditions may be satisfied is as follows:— In front of the central prism system E, see Figure 5, of the rangefinder which combines the beams of light from the two ends of the 40 rangefinder there is mounted a reflector F, for example, a right-angled prism, which receives the rays of light proceeding, say, horizontally from the rangefinder and directs them downwards, say, vertically into the 45 periscope system. The reflector F is carried upon the rangefinder, and moves with it in altitude and therefore remains always in front of the central prism system E of the rangefinder as the rangefinder is moved in 50 altitude. If the reflector F were mounted rigidly in front of the central prism system, then, as the rangefinder was rotated in altitude, the emergent beam from the prism F would not follow a path parallel to a con- 55 stant direction, namely the optical axis of the periscope system. To ensure that the emergent beam will enter the periscope in the required constant direction, unaffected by the altitudinal movement of the range- 60 finder, the reflector F according to this method is mounted upon an axis parallel or thereby to the longitudinal horizontal axis of the rangefinder and means are provided for rotating the reflector F through half the 65 angle traversed by the line of sight of the

rangefinder when moved in altitude, the direction of motion of the reflector F being such that the axis of the emergent beam remains parallel to that of the periscope. The rotation of the reflector F may be effected, 70 say, through the intermediary of spur gearing having a ratio of 2:1, or, say, through the intermediary of levers whose arms are in the ratio of 2:1, or through a combination of levers and gear wheels. 75

One arrangement which combines the use of levers and wheels will now be described with reference to Figures 3, 5 and 6. In these views 5 designates the longitudinal axis of the rangefinder B. 6 an axis parallel 80 to 5, 7 a pivot carried by and moving with the rangefinder B and 8 a pivot carried upon an arm 9 which rotates about the axis 6. The axes 5 and 6 are stationary relative to the periscope. The pivots 7 and 8 move 85 angularly in conformity with the rangefinder. The pivots 7 and 8 are connected by a link 10. The distance between the axes 5 and 6 is fixed and equal to the distance between the axes of the pivots 7 and 8, and 90 since the radius 5—7 is equal to the radius 6—8, the four form a parallelogram and, as the rangefinder B is moved in altitude, the radial directions 5—7 and 6—8 remain parallel. Similarly the connecting link 10 remains parallel to a line connecting 5 and 6. 95 As the line 5—6 is parallel to the optical axis of the periscope A, the connecting link 10 also lies parallel to the axis whatever the altitude movement of the rangefinder. From 100 the upper end of the connecting link 10 there projects at right angles an arm 11 which engages a pin 12 of a rocking arm 13 the spindle of which is provided with a pinion 14 in mesh with an internal spur 105 rack 15 integral with a case 16 which carries the reflector, a prism F. Thus, the prism F is mounted to turn about the axis of the pivot 7. The arm 11 remains always at right angles to the rod 10. Thus, the angular 110 movement of the rangefinder relative to the arm 10 is equal to the altitudinal rotation of the rangefinder B relatively to the periscope. As the rangefinder is moved in altitude, the rocking arm 13 is accordingly 115 moved angularly relatively to the rangefinder by an amount determined by the lengths of the arms 11 and 13 and the reflector F is rotated relatively to the rangefinder and therefore relatively to the central 120 prism system E of the rangefinder by an amount determined by the ratio of the arms 11 and 13 and of the gears 14 and 15. This combined ratio is made such that the rotational movement of the prism F is half that 125 of the rangefinder.

In some cases, as for example in association with rangefinders of the coincidence type, one reflector such as the prism F is employed. In other cases, as for example 130

in association with stereoscopic range-finders, two reflectors, which may be combined or mounted in the same case, may be employed. The reflectors may be of various forms according to the arrangement of the optical parts of the rangefinder and the periscope. In the arrangement described with reference to Figures 3, 5 and 6, the reflector F is a right-angled prism of the roof type.

To maintain constant the position of the focal plane of the image in the field of view of the periscope as the rangefinder B is moved in altitude, one of the periscope lenses may be translated in the direction of the periscope axis by the requisite amount. For example, see Figure 5, the arm 9 is pivoted to rock about the axis 6, the rod 10 is pivoted to the arm 9 at the axis 8, and a holder 17 is also pivoted at the axis 8. The holder 17 carries an objective 18 of the periscope system whose focal plane is coincident with that of the rangefinder, the emergent rays from which are therefore parallel to one another. Upon the lower end of the connecting rod 10 there is a right-angled arm 19 which remains parallel to the arm 11. The outer end of the arm 19 engages with a pin 20 projecting from the holder 17. Thus, as the rangefinder is moved in altitude the objective 18 operates to preserve constant the focal plane of the image as seen in the periscope, the objective 18 being moved vertically by the rod 10 and maintained normal to the beam of light by reason of its support at the axis 8 and by the engagement of the pin 20 with the arm 19.

Associated with the altitudinal movement of the range-finder there is produced in this particular arrangement a small lateral displacement of the link 10 to or from the axis 5-6 and with it a lateral displacement of the objective 18, but, as the emergent rays are parallel to one another, such a displacement does not affect the position of the target image in the field of view of the periscope.

The various parts may be balanced by means of a weight G.

In the constructions illustrated H designates the eyepieces of the perisopic system. Instruments according to this invention may also be provided with a trainer's periscope system, for example, as indicated in Figures 1, 2 and 4, comprising an eyepiece K, prisms 21, 22 and window 23.

I claim:—

1. Apparatus comprising two optical systems one a range-finder system, the other a periscope system, the rangefinder system extending horizontally, the periscope system extending vertically and downwardly from the rangefinder system, the rangefinder system being movable for adjustment angularly about its longitudinal horizontal axis, first means movable for directing rays pass-

ing from the rangefinder system at all angles to which the rangefinder system is adjustable about its horizontal axis vertically into the periscope system, second means movable for maintaining constant the position of the focal plane of the image as seen in the periscope, and means for moving the rangefinder and with it the first and second means all simultaneously for the purposes set forth.

2. Apparatus comprising two optical systems, one a rangefinder system, the other a periscope system, the rangefinder system having a tubular casing extending horizontally, the periscope system having a tubular casing extending vertically and downwardly from the rangefinder, the rangefinder extending laterally at opposite sides of the periscope system, and movable for adjustment angularly about its horizontal axis, first means for directing rays passing from the rangefinder system at all angles to which the rangefinder system is adjustable about its horizontal axis vertically into the second system, second means for maintaining constant the position of the focal plane of the image as seen in the periscope, and means for moving the rangefinder and with it the first and second means all simultaneously for the purposes set forth.

3. Apparatus comprising two optical systems, one a rangefinder system the other a periscope system, the rangefinder system having a tubular casing, the periscope system having a vertical tubular casing and a covering head, the covering head having two tubular sleeves extending laterally from opposite sides of the periscope system, said sleeves being open at their outer ends, the rangefinder being mounted in the covering head arranged with its longitudinal axis horizontally and movable for adjustment angularly about its longitudinal axis and having portions of the rangefinder projecting beyond the outer ends of said sleeves, first means for automatically directing the rays from the rangefinder axially into the perisopic support, second means for maintaining constant the position of the focal plane of the image as seen in the periscope, and means for moving the rangefinders and with it the first and second means all simultaneously for the purposes set forth.

4. Apparatus comprising two optical systems one a rangefinder system, the other a periscope system, the rangefinder system extending horizontally, the periscope system extending vertically and downwardly from the rangefinder system, the rangefinder system being movable for adjustment angularly about its longitudinal horizontal axis, a reflector movable through half the angle of angular adjustment of the rangefinder and located in front of the central prism system of the rangefinder and at the top of the periscope system, an objective of the peri-

scope system movable for maintaining constant the position of the focal plane of the image as seen in the periscope, and means actuated by the rangefinder casing for moving the reflector and the objective, for the purposes set forth.

5. Apparatus comprising two optical systems one a rangefinder system, the other a periscope system, the rangefinder system extending horizontally, the periscope system extending vertically and downwardly from the rangefinder system, the rangefinder system being movable for adjustment angularly

about its longitudinal horizontal axis, reflector means movable angularly for directing rays passing from the rangefinder system at all angles to which the rangefinder system is adjustable about its horizontal axis into the periscope system, a lens of the periscope system movable by translation in the direction of the periscope axis, and means for moving the rangefinder and the reflector means angularly and the lens by translation all simultaneously, for the purposes set forth.

JAMES WEIR FRENCH.
